UNITED STATES PATENT OFFICE.

MONCURE BURKE, OF WASHINGTON, DISTRICT OF COLUMBIA; ROBERT N. VALENTINE, OF WOODBRIDGE, NEW JERSEY, AND PHILIP H. DE WITT, OF WEATHERLY, PENNSYLVANIA, EXECUTORS OF WALTER G. BERG, DECEASED, ASSIGNEES TO LINK-BELT COMPANY, OF PHILADELPHIA, PENNSYLVANIA, AND CHICAGO, ILLINOIS, A CORPORATION OF ILLINOIS.

CHUTE.

No. 918,418.

Specification of Letters Patent.

Patented April 13, 1909.

Application filed July 30, 1908. Serial No. 446,203.

To all whom it may concern:

Be it known that WALTER G. BERG, formerly a citizen of the United States, residing in New York city, New York, but now deceased, did during his lifetime invent certain Improvements in Chutes, of which the following is a specification.

One object of this invention is to construct a double chute particularly adapted for use in connection with coal pockets in loading locomotive tenders with coal, but it will be understood that it may be used for other purposes where it is desired to mix two grades or two different kinds of coal or other material.

A further object of the invention is to provide means for regulating the discharge from each section of the chute.

In the accompanying drawings:—Figure 1, 20 is a perspective view of the improved chute; Fig. 2, is a vertical sectional view on the line 2—2, Fig. 3; and Fig. 3, is a front view of the chute.

A is the framework of the bin or coal bucket.

A', A² are the two coal pockets, each having an inclined floor a.

B is the chute of such a width as to receive coal or other material from both pockets A', 30 A², this chute is pivoted at b and can be raised or lowered, as desired.

c is a counterbalance rod connected to a chain c' from which is hung a balance weight C. The balance weight may be of the compensating type, if desired, without departing 35 from the invention.

The chute has a hood b' at the outer end to prevent the coal or other material shooting past the discharge point when it slides down 40 the chute with any rapidity. The chute has a central partition D made up of two plates d, d' at each side spaced a given distance apart and between these plates is mounted the mechanism for operating the gate. At 45 each side of the chute are plates d' spaced a given distance from the outer edge of the chute, which also protects the operating mechanism.

E and F are two gates—one for regulating 50 the flow of material through one passage B' and the other for regulating the flow of material through the other passage B².

Each gate is constructed as follows:—The gate E has side members E' pivoted at e' to the plates d, d' and have toothed segments 55 e² with which mesh pinions g on each end of the tubular shaft G adapted to bearings in the frame H to which the chute is pivoted. On one end of this tubular shaft is a hand wheel g' by which it is turned. Extending 60 through the shaft G is a shaft I which is adapted to bearings in the frame H at the opposite side of the chute and on this shaft are two pinions i, i which mesh with segments f² on the side members F' of the gate 65 F and on the opposite end of this shaft is a hand wheel i' by which the said shaft is turned, so that on turning the hand wheel i' the gate F can be raised or lowered and on turning the hand wheel g' the gate E can be 70 raised or lowered, and by this means the flow of material can be regulated at will from a fixed point.

The gates are not affected by the movement of the chute when the chute is raised 75 and lowered and they are under the full control of the operator who can regulate the amount of material flowing through each section, and the proper mixture can always be provided by regulating the gates. 80

What is claimed is:—

1. The combination of two pockets situated side by side, a pivoted chute hung from the mouth of the pockets and having a partition dividing the chute into two passageways, one communicating with one pocket and the other communicating with the other pocket, pivoted gates for each passageway, 85 two shafts, one mounted within the other, and a hand wheel for each shaft, one shaft controlling the movement of one gate and the other shaft controlling the movement of the other gate.

2. The combination of a chute having two passageways therein communicating with a 95 single discharge opening, two gates independently mounted in bearings in the said chute, one closing one passageway and the other closing the other passageway, toothed segments on each gate, a tubular shaft having two pinions thereon meshing with the segments of one gate, a long shaft passing through the hollow shaft and having two pinions thereon meshing with the segments 100

on the other gate, and a hand wheel on each shaft at one end of the chute for operating the gates.

3. The combination in a chute having two passageways both communicating with the single discharge opening, partitions, plates on each side of each passageway, two gates, one for regulating the flow of material through one passageway and the other for regulating the flow of material through the other passageway, each gate having a curved body portion and two side members pivoted to the said plates, toothed segments on each side member, two shafts running transversely of the chute, one shaft passing through the other and extending beyond the other, two pinions on each shaft, the pinions

on one shaft meshing with the segments of one gate, the pinions of the other shaft meshing with the segments of the other gate, 20 and a hand wheel for each shaft so that the gates can be operated independently.

In witness whereof, the said MONCURE BURKE, ROBERT N. VALENTINE and PHILIP H. DE WITT, executors of the last will and 25 testament of WALTER G. BERG, deceased, have hereunto set their hands in the presence of two subscribing witnesses.

MONCURE BURKE.
ROBERT N. VALENTINE.
